UNITED STATES PATENT OFFICE

160,303

PLATE OR THE LIKE

Philip Richard Costigan, Port Washington, N. Y., assignor to Castleton China, Incorporated, New York, N. Y., a corporation of New York

Application November 26, 1949, Serial No. 6,270

Term of patent 14 years

(Cl. D44—15)

To all whom it may concern:

Be it known that I, Philip Richard Costigan, a citizen of the United States of America, residing at 52 Hillview Avenue, Port Washington, in the county of Nassau and State of New York, have invented a new, original, and ornamental Design for a Plate or the like, of which the following is a specification, reference being had to the accompanying drawing, forming part thereof.

In the drawing:

Fig. 1 is a top plan view of a plate, showing my new design, and

Fig. 2 is a side elevation thereof.

I claim:

The ornamental design for a plate or the like, as shown.

PHILIP RICHARD COSTIGAN.
